UNITED STATES PATENT OFFICE.

THOMAS BURKHARD, JR., OF BROOKLYN, NEW YORK.

DESIGN FOR A HANDKERCHIEF.

SPECIFICATION forming part of Design No. 27,120, dated May 25, 1897.

Application filed February 11, 1897. Serial No. 623,007. Term of patent 14 years.

To all whom it may concern:

Be it known that I, THOMAS BURKHARD, Jr., a citizen of the United States, residing in the city of Brooklyn, in the county of Kings and State of New York, have invented and produced a new and original Design for a Handkerchief, of which the following is a specification, reference being had to the accompanying drawing, forming a part thereof and representing the said design.

The essential feature of my design consists in a handkerchief having on its face a figure differentiated therefrom and consisting of three circular bands concentric with each other and three pointed wings of curvilinear outline projecting outward from the outer band.

In the drawing, A represents the face of the handkerchief.

abc represent the three concentric circular bands, and ddd the pointed wings of curvilinear outline projecting from the outer band a.

What I claim is—

The design for a handkerchief substantially as herein shown and described.

THOMAS BURKHARD, JR.
